UNITED STATES PATENT OFFICE.

JOHN KITSON, OF JERSEY CITY, NEW JERSEY, ASSIGNOR OF ONE-HALF
TO JOSEPH HOOKER RUSSELL, OF SAME PLACE.

SEWING-MACHINE-COVER FASTENER.

SPECIFICATION forming part of Letters Patent No. 323,342, July 28, 1885.

Application filed March 6, 1885. (No model.)

To all whom it may concern:

Be it known that I, JOHN KITSON, a citizen of the United States, residing at Jersey City, in the county of Hudson and State of New Jersey, have invented new and useful 5 Improvements in Sewing-Machine-Cover Fasteners, of which the following is a specification.

My invention relates to the hooks or studs of the cover and the catch devices of the table, by which the back of the cover is secured to the table preparatory to the fastening of the front of the cover by the lock and key; and it consists of a construction of the catch devices of the table to extend slightly above the surface of the table, and an arrangement 15 of the studs of the cover whereby they do not project below the bottom edge of the cover, suitably for adapting the studs and the catches for interlocking and fastening the cover without any projecting part or portion of the cover-studs below the cover, thus protecting the table from the scratching to which it is now subject by the employment of the fastenings in present use, which consist of cover-studs projecting below the edge of the cover and engaging with catches fitted in flush with the surface of the table, which studs bruise and scratch the table whenever the cover is placed on the table in any other position, except 25 when the studs enter the catches, which is very frequently done.

My invention also comprises a contrivance of the catches which project above the surface to avoid the catching of the goods by them, and I employ pads of leather or other like material in the lower edge of the cover to cushion the cover on the table and prevent the scratching of the table by the cover itself, all as hereinafter fully described, reference 35 being made to the accompanying drawings, in which—

Figure 1 is a plan view of the cover inverted and having the studs for fastening the back edge of the table contrived in accordance with 40 my invention. Fig. 2 is a plan view of the table having the catches for securing the cover as I prefer to arrange them. Fig. 3 is a section of Fig. 2 on line *x x*. Fig. 4 is a section of Fig. 2 on line *y y*. Fig. 5 is a perspective 45 view of a portion of the table, representing

modified forms of the latches. Fig. 6 is a perspective view of a portion of a cover, showing modified forms of the cover attachments that may be used with the catches of Fig. 5; and Fig. 7 represents a modified form of the 55 catches of Fig. 2.

The invention consists, essentially, of hook-catches on the table *a*, projecting above the surface of the same and contrived to hook onto studs or into eyelets of the cover *b*, the object being to utilize these devices for securing the cover at the base of the same in a manner by which the bruising and scratching of the table by the studs of the fastening now in use, which project below the edge of the cover, will 60 be avoided.

The form of the catches and studs may be varied somewhat as I have represented them in the drawings—for instance, the catches *d* and *e*, made of disks of thin sheet metal with 65 a part, *f*, struck up suitably to receive the studs *g* of the cover, and being in such oval form that the goods being worked in the machine will glide over them without catching, will be preferred, the margins of the disks being 70 set in the table flush with the surface, and affording the means of securing them to the table with screws, and the studs *g* on the cover being plain flat strips fastened to the edge of the cover in recesses *h*, and the cover having 75 recesses *i*, in the lower edge, which close over and conceal the catches, or nearly so, when the cover is secured in position; but the oval catches *d e* may be formed on or attached to the end of a wood-screw, as in Fig. 7, to be 80 attached to the cover by screwing into the table.

The catches may, if preferred, consist of hook-headed nails or screws *i'* or *j*, driven or screwed into the table, as in Fig. 5, with bushed 85 sockets *k* formed in the inside of the cover *b*, as in Fig. 6; but I prefer the oval-head catches *d* or *e* and the studs *g*.

I propose to use the ordinary lock *l* and catch for the front side of the cover, with my 90 improved fastening for the back, and will cushion the bottom of the cover with elastic pads *n*, of leather or other improved material, to protect the surface of the table from being 95 bruised and scratched by it. These pads may 100

be connected by pressing them tightly into holes bored in the lower edge of the cover at the corners or elsewhere, or may be otherwise secured.

- 5 For the catches *d e* and studs *g* I prefer the arrangement shown, in which the studs *g* are made to enter the catches by pushing the cover from the front of the table backward, but the arrangement may be in the reverse 10 thereof, to make the connection by shifting the cover forward, which is the preferable arrangement for the contrivance of the fastening, as in Figs. 5 and 6, but this may also be contrived to shift from the front backward, as 15 preferred.

Having thus described my invention, what I claim, and desire to secure by Letters Patent, is—

- 20 1. The combination, with a sewing-machine table having hook-catches for the back of the cover projecting above its surface, of a cover having studs or equivalent fastenings located above its lower edge, and arranged and adapted to engage said catches by a backward or 25 forward movement of the cover with the back

edge of the cover resting on the table, substantially as described.

2. The combination, with a sewing machine table having catches with oval heads *f*, projecting above its surface, of a cover having 30 studs *g*, located above the lower edge of the cover and adapted to engage said catches above the surface of the table, substantially as described.

3. The combination, with a sewing-machine 35 table having catches with oval heads *f*, projecting above its surface, of a cover having studs *g*, located above the lower edge of the cover and adapted to engage said catches above the surface of the table, said cover also 40 having recesses *i*, adapted to close over the catches substantially as described.

In witness whereof I have hereunto signed my name in the presence of two subscribing witnesses.

JOHN KITSON.
